UNITED STATES PATENT OFFICE.

JOHN F. BREEN, OF HINGHAM CENTER, MASSACHUSETTS.

SLIDING HINGED LAST.

1,407,723.

Specification of Letters Patent. Patented Feb. 28, 1922.

Application filed March 17, 1921. Serial No. 453,093.

To all whom it may concern:

Be it known that I, JOHN F. BREEN, a citizen of the United States, residing at Hingham Center, in the county of Plymouth and

5 State of Massachusetts, have invented a new and useful Sliding Hinged Last, of which the following is a specification, reference being had therein to the accompanying drawings.

10 My invention relates to hinged lasts for boots and shoes and more especially to a last in which the heel part is adapted to have a sliding movement with respect to the fore part when being removed from the shoe.

15 The main object of my invention is the provision of a hinged last for boots and shoes so constructed that after the boot or shoe has been finished, the last may be removed therefrom without difficulty and without stretching or injuring the boot or shoe.

20 Another object of the invention is to provide a hinged last so constructed that the parts will not separate or turn on the hinge when the sole of the last is subjected to 25 strain during the shoe manufacturing processes.

A further object of the invention is the provision of a hinged last simple and efficient and of low cost of construction.

30 Other objects of the invention will be more fully set forth and described hereinafter.

My invention contemplates a last in which the heel part is connected to the fore part by one or more hinges so constructed that the 35 parts thereof are capable of a sliding or telescopic movement in relation to each other, whereby the heel part has both a sliding and a pivotal movement in relation to the fore part when the last is being placed 40 in or removed from a shoe.

In the drawings illustrating the preferred embodiment of my invention, Figure 1 is a top plan view of a last constructed and adapted to be operated in accordance with my invention; Fig. 2 is a central longitudinal vertical sectional view on line 2—2 in Fig. 1, showing the last in normal position, and Fig. 3 is a similar view showing the heel part raised in relation to the fore part prepara-

45 tory to removing the last from the shoe, the position of the heel part after it has been moved pivotally on the hinges being shown in dotted outline.

In the drawings illustrating the preferred 50 embodiment of my invention is shown a last comprising a fore part 5, a heel part 6 and a

locking block 7. These parts are formed by taking the last, after it has been turned, and cutting it transversely on the line 8, which is curved longitudinally the last in order to 60 separate the portion 7 which serves as a locking block. The remaining portion of the last is then cut transversely on the line 9, this cut extending from the bottom of the last at the shank portion upwardly slanting 65 toward the fore part, thereby resulting in the fore part 5 and the heel part 6 respectively.

The fore and heel parts are then hinged together in the following manner. The removal of the locking block 7 leaves a curved 70 face 10 on the heel part and a curved face 11, which is a continuation of the face 10, on the fore part. Two narrow longitudinal and fairly deep recesses 12 are then cut in the faces 10 and 11 and within these recesses are 75 set two hinges by which the fore part and the heel part are hinged together. The construction of these hinges constitutes an important feature of my invention because they are intended to permit of both sliding and pivotal 80 movements of the heel part in relation to the fore part.

Although the hinges may be made in any suitable manner which will permit of the said two movements, I prefer to construct 85 them as shown in the drawings, each hinge being made up of two leaves 16 and 18. The leaf 16 is provided with a longitudinal slot 20 which is preferably wider at the toe end of the last than at the other end, and the leaf 18 is slightly curved on its longitudinal axis and is split nearly its entire length 90 to form a recess 22. The recessed end of the leaf 18 carries a pin 24, which pin lies within the slot 20 of the leaf 16 when the 95 two are assembled, the leaf 16 being sufficiently thin to move freely within the recess 22 in the leaf 18. The hinge is secured in position on the fore and heel parts of the last connecting the two; a pin 26 is arranged in the toe end of the leaf 16 and a pin 28 in the heel end of the leaf 18, these pins passing through the last for the purpose of holding the hinges in place in the parts.

105 Any suitable means may be provided for holding the locking block in place upon the last when the latter is placed within the shoe and for this purpose I provide a pin 30 set fixedly in the face 11 of the fore 110 part 5 and turned toward the heel part, and a pin 32 set in a recess 34 in the face

10 of the heel part 6, this pin being backed up by a spring 36 so that it may be retracted within the recess 34 when the locking block 7 is being adjusted in position. 5 The locking block 7 is provided with a curved hole 40 adapted to receive the curved pin 30 and with a hole 42 to receive the pin 32. It will also be found necessary to provide the inner face of the locking block 10 with recesses 44, since the hinges project above the curved faces 10 and 11 of the heel and fore parts of the last.

In use, my last is assembled as shown in Fig. 2 of the drawings, with the locking block 7 held against displacement by the two pins 30 and 32 and the locking block in turn holds the fore part 5 and heel part 6 against separation at the joint 9 when the sole of the last is subjected to strain or pressure during the making of the shoe. After the shoe is completed, the pin 32 may be pressed down with a suitable tool inserted in the hole 54 and the locking block thereby released so that it may be removed from the shoe. The heel part 6 may then, with the assistance of a suitable tool inserted in the hole 50, be pulled upwardly into the position shown in Fig. 3 of the drawings. During this movement the leaf 16 is turned a short distance upon the pin 26 as a pivot, the leaf 18 moving very slightly, if any, on its pivot, because the slot 20 at the heel end is slightly larger than the pin 24 and permits of a slight movement of the pin 24 upwardly in the slot 20 when the leaf 18 is carried upwardly by the movement of the heel part. During this entire movement the heel part remains in sliding engagement with the fore part on the joint 9 and when the heel part has reached the position shown in Fig. 3 it will be observed that the total length of the last has become shortened. The shortening of the last accomplished in this way disengages the curved face of the heel part from the heel of the shoe so that from the position shown in Fig. 3 the heel part 6 may be pivotally turned on the hinges and removed from the heel of the shoe without strain and without stretching or disturbing the curved shape of the heel of the shoe. After the heel part 7 has been raised into the position shown in dotted outline in Fig. 3, the last may then be entirely removed from the shoe.

It will be observed that the foregoing result is secured by making the joint or cut 9 in the last slope toward the fore part of the last and the shortening of the last during this operation may be regulated to some extent by varying the slant of said cut from a vertical line.

Although I have shown and described my invention as being embodied in a last employing two hinges, it is to be understood

that one hinge may be used in place of two hinges if desired. When but one hinge is used, the slot 12 should be of such restricted width that the hinge fits tightly therein to prevent any lateral motion either of the hinge or the parts of the last in relation to each other.

It is further to be understood that I do not desire to limit myself to the precise form of hinge herein shown and described, since my invention may be embodied in other forms of hinges in which the hinge parts have a relative movement at the point of their pivoted connection.

What I claim is:

1. In a hinged last, the combination of a fore part and a heel part connected together by a hinge made up of two leaves, each of said leaves being pivotally connected to one of said parts and said two leaves being pivotally connected together yet capable of a telescopic movement of the pivot point. 80

2. In a hinged last, the combination of a fore part and a heel part connected together by a hinge made up of two leaves, each of said leaves being pivotally connected to one of said parts and said two leaves being pivotally connected together; one of said leaves being provided with a slot at the pivot point to permit of a sliding movement of one leaf in relation to the other leaf. 90

3. In a hinged last, the combination of a fore part and a heel part connected together by a hinge made up of two leaves, each of said leaves being pivotally connected to one of said parts and said two leaves being pivotally connected together, one of said leaves being provided with a longitudinal open recess adapted to receive the other leaf and the other of said leaves being provided with a slot to receive the pivot pin whereby the two leaves are permitted to have a relative movement at the pivot point. 100

4. A hinged last comprising a fore part and a heel part connected together by a hinge, said hinge being made up of two leaves each pivotally connected to one of said parts and being pivotally connected together by a pin, one of said leaves being provided with a longitudinal slot within which said pin moves in order to permit said leaves to have a sliding movement with relation to each other at the pivot point. 110

5. A hinged last comprising a fore part, a heel part and a hinge connecting said two parts and made up of two leaves, each of which is pivotally connected to one of said parts; the two leaves of said hinge being so connected to each other as to permit each of said last parts to have both a sliding and a pivotal movement in relation to the other last part. 120

6. A hinged last comprising a fore part, a heel part and a hinge connecting said two parts; said hinge comprising two leaves, 130

each of said leaves being pivotally connected to one of said parts and said two leaves being pivotally connected together; one of said leaves being split longitudinally 5 at its pivoted end to receive the other leaf and one of said leaves being provided with a slot at the pivot point to permit said two leaves to have a telescopic movement at the pivot point thereby permitting each last part to have both sliding and pivotal movements 10 in relation to the other last parts.

In witness whereof, I hereunto set my hand this sixteenth day of March, 1921.

JOHN F. BREEN.
